OSCAR TERVO, OF QUINCY, MASSACHUSETTS, ASSIGNOR OF ONE-HALF TO KONSTA HILL, OF QUINCY, MASSACHUSETTS.

SUBMARINE ESCAPE BOAT.

1,405,728.

Specification of Letters Patent.

Patented Feb. 7, 1922.

Application filed February 12, 1921. Serial No. 444,457.

To all whom it may concern:

Be it known that I, OSCAR TERVO, a citizen of Russia, residing at Quincy, in the county of Norfolk and State of Massachusetts, have 5 invented certain new and useful Improvements in Submarine Escape Boats, of which the following is a specification.

This invention relates to a combination submarine and life boat, the principal object of which is to equip a submarine with a 10 life boat which may be used by the submarine crew in an emergency.

Another object of the invention is to provide a life boat attached to a submarine 15 which is readily detachable from the submarine and which is navigable entirely independently of the submarine so as to carry the crew to a point of safety.

A still further object of the invention is 20 to provide a life boat which is attached to the submarine and is submersible simultaneously with the latter, the boat being of a construction which will not appreciably retard the progress of the submarine or otherwise 25 inconvenience the latter, at the same time being ample to accommodate the occupants of the submarine and to carry them in convenience and safety.

The above and other objects of this invention will be in part described and in part understood from the following description of 30 the present preferred embodiment of the invention taken in connection with the accompanying drawings, wherein:

35 Fig. 1, is a longitudinal sectional view of a device constructed in accordance with this invention, a portion of the submarine being broken away.

Fig. 2, is a vertical sectional view of the 40 same.

Fig. 3, is a fragmentary detail bottom plan view of the hatch which leads into the life boat.

Fig. 4, is a detail fragmentary sectional view taken through the hatch way and illustrating the manner of mounting the hatches on the life boat and the submarine, and

50 Fig. 5, is a fragmentary sectional view of the device showing a portion of the life boat in bottom plan and illustrating the manner of connecting the boat releasing mechanism thereto.

In the drawings, a portion of a submarine 55 boat 6 is shown which may be of the usual or any desired configuration. Preferably

the submarine is equipped with bulkheads 7 arranged in a manner well known in the art.

Positioned between the bulkheads 7, and preferably at the rear of the conning tower of the submarine, a hatchway 8 is mounted. 60 This hatch-way is of a cylindrical configuration and extends downwardly into the submarine for an appreciable distance. The lower end of the hatch-way has a right angled flange 9 fixedly secured to its inner 65 periphery. This flange is connected with a concentric ring 10 by means of connecting straps 11. The upper end of the hatch-way extends above the top of the submarine and is secured to the latter in any desired 70 manner.

A hatch 12 is hingedly connected to the ring 10 and is equipped with a pair of levers 13 and 14, the former of which is arranged on top of the hatch and the latter arranged 75 beneath the hatch. The said lever 14 has a portion of one of its ends extended to provide a locking nose 15 which is engageable with a lug 16 arranged on the inner periphery of the ring 10. It will be noted that the 80 levers 13 and 14 are connected by a shaft shown by dotted lines in Fig. 4. When pressure is exerted upon either one of said levers, the shaft is rotated to impart a corresponding movement to the other lever. 85

A life boat 17, constructed in accordance with this invention, is mounted upon the submarine 6. Preferably, the life boat is completely enclosed, in much the same manner as a submarine, and is equipped with an 90 engine 18 which communicates power to a propeller 19. Moreover, the life boat has hatches 20 formed in its top which may be of the usual or any desired construction. Lights 21 depend from the ceiling and may 95 be lighted by a storage battery or other source of energy which may be, if desired, stored in a chamber 22 formed in one end of the boat. The opposite end of the boat is divided to provide a compartment 23 which 100 may constitute a gasoline tank for supplying the engine with fuel. A rudder shaft 24 extends vertically through the rear end of the boat and has its rudder 25 arranged directly to the rear of the propeller 19. If desired, 105 seats, such as shown at 26, may be formed along the inner sides of the boat so as to conveniently carry the passengers.

Depending from the boat 17 is an annulus 27 which is provided with a recess, the latter 110

carrying a gasket 28. The gasket 28 is engaged with the upper terminal of the hatch-way 8 and is preferably made of rubber so as to form a water-tight connection between the life boat and the submarine.

In order to hold the submarine and life boat in engagement with each other a suitable locking means generally designated 29 is provided which consists of a pair of segmental gears 30 pivotally mounted on the bottom of the boat 17. The locking means further embodies levers 31, one end of each of which is pivotally engaged with one of the gears 30, while the opposite end is adapted for slidable engagement through locking blocks 32 carried by the boat and locking blocks 33 carried by the submarine. The levers 31 are arched around the hatch-way 8 in order to prevent interference of the levers with persons passing through the latter. Auxiliary locking levers 34 are pivotally engaged with the gears 30 and are likewise slidably arranged through locking blocks 32 and 33. The gears 30 are simultaneously operated by a pinion 35 which is mounted upon the lower end of a rod 36, the latter extending upwardly through a water-tight connection in the bottom of the boat and having an operating wheel 37 formed on its upper end. Rotation of said wheel 37 imparts movement to the levers 31 and 34 to disengage the same from the blocks 32 and 33 so as to permit the life boat to free itself from the submarine. In order to limit the movement of said levers, complementary abutment blocks 38 are formed upon the levers 31 and 34 and likewise upon the top of the submarine.

In order to prevent a vacuum from being formed in the hatch-way 8, which might retard disengagement of the life boat from the submarine, even after the locking mechanism has been released, suitable mechanism is provided to permit a gradual influx of water into the hatch-way 8 simultaneously with the disengagement of the locking means. The said mechanism consists especially of a valve 39 which is mounted in a right angled conduit, one end 40 of the conduit constituting an inlet which is arranged in proximity to the outer periphery of the hatch-way 8, as shown to advantage in Fig. 5. The opposite end of the conduit constitutes an outlet 41 which is arranged on the interior of the hatch-way. Movement of the valve is controlled by a valve lever 42, one end of the latter being pivotally mounted upon one of the gears 30 and the opposite end pivotally connected with a link 43, which engages the valve. Consequently, when the gears 30 are operated, the valve 39 will be opened, thereby permitting water to flow into the hatchway.

Depending from the boat 17 is a circular collar 44, which is arranged concentric to

the annulus 27 and spaced therefrom. The said collar depends into the hatch-way 8, as shown in Fig. 4, and is equipped with a hatch 45 which is identical in configuration to the hatch 12 and is connected to the collar 44 in the same manner as the hatch 12 is connected to the ring 10.

In order to control the velocity with which the boat 17 will rise to the surface of the water, suitable ballast blocks 46 are provided which may, if desired, be engaged with the bottom of the boat, at the sides of the latter, as shown in Fig. 2. Preferably, these blocks are channeled as indicated at 47 to receive brackets 48, the latter being mounted upon the boat. Detachable releasing levers 49 extend through the side walls of the boat into engagement with the ballast block 46 so as to disengage the latter from the brackets 48 when desired. These levers 49 may be arranged beneath the seats 26 so as to be out of the way of the occupants of the boat, at the same time being readily accessible if occasion should demand. If upon operating the locking mechanism 29 it is found that the weight of the boat is too heavy to permit proper elevation, any one or all of the ballast blocks may be released.

In use of this device, if perchance the submarine should be rendered inoperative for any reason, the crew of the submarine may enter the life boat 17 by first opening the hatch 12 following which the hatch 45 is opened, thereby placing the submarine and life boat in direct communication. After the crew has transferred from the submarine to the life boat, the hatches are locked in an apparent manner and the locking mechanism 29 released by the manipulation of the operating wheel 37. The life boat will be carried to the surface of the water, because of its buoyancy, and may be then operated on the surface of the water in a manner well known in the art. When the desired destination has been reached, the crew may exit through the hatches 20.

In using this device it is preferred that the life boat be arranged on the submarine at the rear end of the latter in view of the fact that as a rule the forward end of the submarine, in front of the conning tower, equipped with various instrumentalities. Since it would be unnecessary for the life boat to carry any appreciable quantity of supplies, etc., it is apparent that practically the entire interior thereof may be used for accommodating the crew which is transferred from the submarine. It is to be understood that various changes may be made in this device, especially in the details of construction, proportion and arrangement of parts within the scope of the appended claims.

What is claimed is:

1. A life boat attachment for submarines,

- in combination with a submarine boat, a life boat arranged on top of the submarine, a hatch-way mounted in the submarine and communicable with the life boat, independent hatches carried by both the life boat and submarine boat to close communication through the hatch-way, means for disconnecting the life boat from the submarine boat, and valve means controlled by said second mentioned means to admit water pressure to the underside of the life boat hatch when the first said means is operated to prevent a vacuum from forming in the hatch-way.
- 15 2. An attachment for submarines including a life boat mounted upon the submarine, a hatchway mounted in the submarine with its upper end projecting above the latter, means carried by the life boat to engage the hatchway, locking rods for holding said means snugly in engagement with the hatchway, means to operate said rods for releasing the life boat, and a valved conduit communicating with said hatchway and automatically released by the valve operating means to permit gradual introduction of water into the hatchway substantially as described.

In testimony whereof I affix my signature in presence of two witnesses.

OSCAR TERVO.
